(57) **CLAIM**

The ornamental design for an endboard, as shown and described.

DESCRIPTION

FIG. 1 is a perspective view of a first embodiment of an endboard showing my new design, and including broken lines indicating representative environmental elements;

FIG. 2 is a front elevational view thereof, and including broken lines indicating representative environmental elements;

FIG. 3 is an end elevational view thereof;

FIG. 4 is a top view thereof; and,

FIG. 5 is a perspective view of a second embodiment of an endboard showing my new design in a side rail configuration, and including broken lines indicating representative environmental elements.

The views of the endboard not shown form no part of the claimed design. The broken lines depicting a bed in FIGS. 1, 3 and 5 represent environmental elements only and form no part of the claimed design.
